UNITED STATES PATENT OFFICE.

WILLIAM C. HEDGCOCK, OF CHICAGO, ILLINOIS, ASSIGNOR TO AMERICAN STEEL FOUNDRIES, OF CHICAGO, ILLINOIS, A CORPORATION OF NEW JERSEY.

REVERSIBLE FULCRUM MECHANISM.

Application filed September 23, 1921. Serial No. 502,771.

To all whom it may concern:

Be it known that I, WILLIAM C. HEDGCOCK, a citizen of the United States, residing at Chicago, in the county of Cook and State of Illinois, have invented certain new and useful Improvements in Reversible Fulcrum Mechanism, of which the following is a specification.

This invention relates to brake beams and 10 more particularly to reversible fulcrums forming a part thereof.

An object of the invention is to provide a simple and efficient reversible fulcrum arrangement for brake beams which is adapted 15 to meet the requirements for a fulcrum which may be used right-hand and left-hand and at the same time prevent the existence of lost motion and properly perform its function as a strut of the brake beam truss.

20 This and other objects are accomplished by means of the arrangement disclosed on the accompanying sheet of drawings, in which—

Figure 1 is a fragmentary top plan view of a brake beam embodying my invention;

25 Figure 2 is a fragmentary side elevation of the fulcrum body and showing the tension and compression members and a wedge associated therewith in section; and

Figure 3 is a sectional view taken in the 30 plane of line 3—3 of Figure 2.

The various novel features of my invention will be apparent from the following description and drawings and will be particularly pointed out in the appended claims.

35 Referring to the figures of the drawings it will be noted that I have disclosed my invention in connection with a truss type of brake beam including a compression member 10, tension member 11 and a fulcrum 12 extending therebetween. The reversible ful-

40 crum includes a main body portion 13 having spaced arms 14 between which a brake lever, not shown, may be pivotally mounted. The rear end of the fulcrum body 13 is provided 45 with an integrally formed projection 15 which in this instance extends through registering openings 16 and 17 of two overlapping portions 18 and 19 respectively of a band 20 which surrounds or embraces the compres-

50 sion member 10. After the projection 15 is passed through openings 16 and 17 it is upset to form a head 21.

For positioning the band 20 on the compres- 55 sion member said band is provided with a depression or seat 22 for the reception of a

corresponding projecting portion 23 formed on the web 24 of the compression member 10. For making the fulcrum connection between the compression and tension members absolutely rigid and overcoming any lost motion, a wedge 25 is driven between the front surface of the web 24 of the compression member and the head 21 formed integrally with the fulcrum body 13. This wedge is provided with an inclined surface 26 by 60 means of which the wedging action is gradually applied. When the wedge is driven to its final wedging position further movement in the same direction is prevented by the lip 27 which engages a portion of the band 20. The tongue 28 of the wedge may then be bent over into a locking position, as shown in Figure 1, for preventing accidental withdrawal of the wedge. 70

Not only does the wedge take up all lost 75 motion between the parts in question, but it yieldably holds the reversible fulcrum body 13 in adjusted position.

The rear end of the fulcrum body is provided with angular faces 29 for engagement 80 with a laterally turned lip 30 on the portion 18 of band 20 for limiting reversible movements of the fulcrum.

The front end of the fulcrum body has pivotally connected thereto a tension rod 85 saddle 31 which permits reversible movements of the fulcrum body.

By means of this arrangement the fulcrum body forms a perfect strut in the brake beam truss and may be reversed and yieldably held 90 in adjusted position.

It is my intention to cover all modifications of the invention falling within the spirit and scope of the following claims.

I claim:

1. In a brake beam, the combination of a compression member, a separate closed band embracing said compression member, a reversible fulcrum body having a headed projection whereby it is rotatably secured to 100 said band, and means interposed between said compression member and said headed projection for preventing lost motion longitudinally of the fulcrum body.

2. In a brake beam, the combination of a 105 compression member, a separate closed band embracing said compression member, a reversible fulcrum body having a headed projection whereby it is rotatably secured to said band, and a wedge located between said 110

headed projection and compression member for preventing lost motion longitudinally of said fulcrum body.

3. In a brake beam, the combination of a compression member, a separate closed band operatively associated with said compression member, a reversible fulcrum body having a headed projection whereby it is rotatably secured to said band, and means interposed between said compression member and headed projection for preventing lost motion longitudinally of said fulcrum body.

4. In a brake beam, the combination of a compression member, a reversible fulcrum body, a band operatively associated with said compression member and fulcrum body and having a projecting portion, means interposed between said compression member and fulcrum body for preventing lost motion longitudinally of the fulcrum body, said fulcrum body being adapted to engage said projecting portion for limiting reversible movements of said fulcrum body.

5. In a brake beam, the combination of a compression member, a closed band having overlapping apertured portions and embracing said compression member, a fulcrum body having a projection extending through the apertures of said overlapping band portions, and a wedge between said compression member and projection for preventing lost motion longitudinally of said fulcrum body.

6. In a brake beam, the combination of a compression member, means embracing said compression member, a fulcrum body having

a projection extending through said means, and a wedge between said compression member and projection for preventing lost motion longitudinally of said fulcrum body, 40 said means and fulcrum body having cooperating portions for limiting reversible movements of said fulcrum body.

7. In a brake beam, the combination of a compression member, a band embracing said compression member, said compression member and band having cooperating means for preventing a given movement of said band with respect to said compression member, a reversible fulcrum body extending beyond 50 said band, and a wedge engaging said compression member and a portion of said fulcrum body for preventing lost motion longitudinally of said fulcrum body.

8. In a brake beam, the combination of a compression member, a band embracing said compression member, said compression member and band having cooperating means for preventing a given movement of said band with respect to said compression member, a reversible fulcrum body extending beyond 60 said band, and a wedge engaging said compression member and a portion of said fulcrum body for preventing lost motion longitudinally of said fulcrum body, said 65 fulcrum body and band having cooperating portions to limit reversible movements of said fulcrum body.

Signed at Chicago, Illinois, this 15th day of September, 1921.

WILLIAM C. HEDGCOCK.
